(57) CLAIM

The ornamental design for a sofa with cushions, as shown and described.

DESCRIPTION

FIG. 1 is a top, front right side perspective view of a first embodiment of my new design for a sofa with cushions; FIG. 2 is a top, front right side perspective view with the cushions in an alternate position of use;

FIG. 3 is a front perspective view with additional cushions near the arms;

FIG. 4 is a front perspective view with the additional cushions near the arms in an alternate position of use;

FIG. 5 is a front perspective view with the additional cushions near the arms in a second alternate position of use;

FIG. 6 is a front perspective view with the cushions in an alternate configuration;

FIG. 7 is a left side perspective view;

FIG. 8 is a top, front right side perspective view of a second embodiment of my new design for a sofa with cushions, with the cushions removed for clarity of illustration;

FIG. 9 is a top, front right side perspective view with a pair of cushions at the armrests;

FIG. 10 is a top, front right side perspective view with the pair of cushions at the armrests in an alternate configuration and an additional cushion along the backrest;

FIG. 11 is a top, front right side perspective view in an alternate configuration of use;

FIG. 12 is a top, front right side perspective view in a second alternate configuration of use;

FIG. 13 is a top, front right side perspective view in a third alternate configuration of use;

FIG. 14 is a top, front right side perspective view of a third embodiment of my new design for a sofa with cushions;

FIG. 15 is a top, front right side perspective view with the cushions removed for clarity of illustration;

FIG. 16 is a top, front right side perspective view with the cushions in an alternate configuration of use;

FIG. 17 is a top, front right side perspective view with the cushions in a second configuration of use;

FIG. 18 is a top, front right side perspective view with the cushions in a third configuration of use;

FIG. 19 is a top, front right side perspective view with the cushions in a fourth configuration of use;
FIG. 20 is a top, front right side perspective view with the cushions in the fourth configuration of use with the cushions in an alternate position of use; and,
FIG. 21 is a top, front right side perspective view with the cushions in a fifth configuration of use.
